UNITED STATES PATENT OFFICE.

WILLIAM L. PFEFFERKORN AND ALBERT P. SCHLOERB, OF MILWAUKEE, WISCONSIN,
ASSIGNORS OF ONE-THIRD TO AUGUST H. HAMMETTER, OF MILWAUKEE, WISCONSIN.

DESIGN FOR A PEDESTAL-TABLE.

48,986.

Specification for Design.

Patented May 2, 1916.

Application filed December 11, 1915. Serial No. 66,383. Term of patent 7 years.

To all whom it may concern:

Be it known that we, WILLIAM L. PFEFFERKORN and ALBERT P. SCHLOERB, citizens of the United States, residing at Milwaukee, in the county of Milwaukee and State of Wisconsin, have invented a new, original, and ornamental Design for a Pedestal-Table, of which the following is a specification, reference being had to the accompanying drawing, forming part thereof.

The figure is a perspective view of a pedestal table showing our new design.

We claim—

The ornamental design for a pedestal table as shown.

WILLIAM L. PFEFFERKORN.
ALBERT P. SCHLOERB.
